UNITED STATES PATENT OFFICE.

JOHN MANNING VAN HEUSEN, OF JAMAICA PLAIN, MASSACHUSETTS, ASSIGNOR TO
VAN HEUSEN PRODUCTS, INC., A CORPORATION OF DELAWARE.

FOLDING COLLAR.

Application filed November 16, 1921. Serial No. 515,610.

To all whom it may concern:

Be it known that I, JOHN MANNING VAN HEUSEN, a citizen of the United States of America, residing at Jamaica Plain, in the 5 county of Suffolk, State of Massachusetts, have invented certain new and useful Improvements in Folding Collars; and I do hereby declare the following to be a full, clear, and exact description of the invention, 10 such as will enable others skilled in the art to which it appertains to make and use the same.

This invention relates to improvements in folding or turn down collars adapted to be 15 worn without starching.

The improved collars of the present invention have either their folding portion or their neck band portion or both of a single 20 piece of fabric coated with a flexible and washable layer of stiffening material integrally combined therewith.

According to one embodiment of the invention the collar is a built up collar having 25 its fold portion made of a single piece of fabric coated in the manner above mentioned, and having a separate neck band, which may be built up of separate pieces of 30 fabric, to the upper edge of which the folded portion is secured.

According to another embodiment of the invention, both the neck band and the folding 35 portions of a built up collar are made up of single pieces of fabric of the character mentioned.

According to a still further embodiment 40 of the invention, the collar is a one piece collar having its folding portion coated and stiffened in the manner above described and with its neck band portion either free from 45 coating or likewise coated, but with a natural fold portion at the upper edge of the folding or turn down portion, at which the 50 collar will naturally fold.

The fabric used in the improved collar 45 construction of the present invention is a relatively heavy fabric, for example, a light weight two-ply fabric, which is considerably heavier than an ordinary single ply fabric, but which may nevertheless be lacking in a desirable degree of stiffness.

Different coating materials may be used 50 for coating the collar fabric. Coating agents such as cellulosic binding materials may thus be used which are insoluble in water and which will adhere to the woven

fabric in the form of a flexible and washable stiffening layer. For example, solutions of cellulose derivatives, such as cellulose nitrate in suitable solvents, or solutions of cellulose in cellulose solvents, such as 60 cuprammonium solutions, or solutions of viscose, can be used. The coating should be one which will penetrate the fabric to a sufficient degree without however appearing on the opposite side of the fabric, so that the 65 outside of the fabric will have the ordinary appearance of a woven fabric.

The binding and coating material can be applied in different ways. In the case of a built up collar, the folding portion, for example, can be coated with the cellulosic solution and the edge then turned, for example, in a folding machine, the coating serving in this case to cement the turned edge in place. In the case of a one piece collar, 70 with one piece of fabric forming both the neck band and the fold portion, the fold portion can be similarly coated, or both the neck band and the fold portion can be similarly coated, except at the fold line where 75 increased stiffness is not desired.

After the fabric has been coated, the coating can be modified to convert it into its final form. In the case of a solution of a cellulose derivative in an organic solvent, 80 the solvent may be evaporated and the insoluble coating thus formed. In other cases, the coating may be converted by heat or by heating and pressure, for example, in the case of solutions of viscose when they are 85 used to coat the fabric.

Instead of applying a separate coating material the surface of the fabric itself may be acted upon by chemicals which will combine therewith to form a surface layer of 90 increased stiffness.

The invention will be further described in connection with the accompanying drawings illustrating certain embodiments thereof in which—

Figure 1 shows in perspective a completed collar embodying the invention.

Figure 2 is a view of the collar of Figure 1 showing the inside of the collar when unfolded,

Figure 3 is a sectional view of the collar of Figure 1,

Figure 4 is a sectional view of a modified construction.

The collar of Figures 1, 2 and 3 is a one

- piece collar, that is with a single piece of fabric forming both the neck band portion 2 and the folding portion 1 of the collar. The folding portion has a layer of the stiffening material 3 secured thereto on the inside so that this coating will be concealed from view when the collar is worn. The edge binding may be of varying construction. It may be made in the manner illustrated by folding in the edge of the collar and stitching it. The coating of stiffening material may in this case serve to cement the turned edge of the folding portion of the collar. The amount of the coating may be decreased at the edge of the collar, or a part of the coating may even be forced out from between the thicknesses of the fabric when the edge is turned and pressed in the folding machine.
- 20 The collar of Figure 4 is a built up collar having a separate neck band 2^a made of two separate pieces of fabric with their edges turned in and stitched together and with the folding portion secured between them at the upper edge of the neck band. The folding portion 1^a is provided with a coating 3^a and an edge binding 4^a similar to those of Figure 3.

- When the coating material is applied only to the folding portion of the collar, the edge of the coating is made curvilinear as indicated at 6 in Figure 2 so that a curvilinear fold line will be provided at the edge of the stiffened portion of the fabric. This fold line will therefore be formed of an unstiffened portion of the fabric so that the collar will naturally fold along this line.
- The completed collars of the present invention are accordingly of a composite character, in that they are made up in part or in whole of single thicknesses of fabric which where exposed to view on the outside present the same appearance as an ordinary fabric collar, but with the inside of the fabric stiffened by the coating applied thereto which is of such a character that the collar will nevertheless be flexible and washable, but will have an increased degree of stiffness more or less comparable with that of a

starched collar. That is, the coating material does not penetrate to the outside of the fabric and is not of such a plastic character that it makes the collars unduly stiff or prevents them from being laundered in the usual way, so that the fabric presents the appearance of a fabric collar and can be handled much the same as a fabric collar.

Where the stiffening layer is made by treating the surface of the fabric itself on one side, it will be integral, as distinguished from an applied stiffening layer. It will be evident that the invention is applicable to collars of various styles and that different fabrics may be used.

I claim:

1. A folding or turn-down collar made up of a neckband portion and a folding or turn-down portion, one of said portions having a relatively thick and stiff coating layer in intimate contact with and firmly adhering to the threads on the inner surface of the said portion, the said coating being insoluble in water and serving materially to stiffen and support the collar, the outer exposed surface of the coated portion of the collar being unaltered in appearance and untouched by the coating layer.

2. A folding or turn-down collar comprising a neckband portion and a turn-down portion, the said turn-down portion having a relatively stiff cellulosic coating layer in intimate contact with and firmly adhering to the threads on the inner surface of the said turn-down portion, the said cellulosic coating layer serving to increase the thickness and stiffness of the turn-down portion of the collar, and the outer exposed surface of the turn-down portion being unaltered in appearance and untouched by the cellulosic coating layer.

3. A collar of the construction defined in claim 1, said collar being made of multiple-ply interwoven fabric.

4. A collar of the construction defined in claim 2, said collar being made of multiple-ply interwoven fabric.

In testimony whereof I affix my signature.

JOHN MANNING VAN HEUSEN.
